United States Patent Office

Des. 218,100
Patented July 21, 1970

218,100

DISPLAY CONSOLE

Dave H. Dabney, Eugene, N.J., assignor to The Western Union Telegraph Company, New York, N.Y., a corporation of New York

Filed Feb. 10, 1969, Ser. No. 15,703

Term of patent 14 years

Int. Cl. D14—02

U.S. Cl. D26—5

FIG. 1

FIG. 2

FIG. 4

FIG. 3

FIG. 1 is a perspective view of a display console showing my design.

FIG. 2 is a top plan view thereof; and

FIG. 3 is a front elevational view thereof.

FIG. 4 is a side elevational view thereof. The broken line representation of indicia in FIGS. 1, 2 and 3 is for purposes of illustration only.

I claim:

The ornamental design for a display console, substantially as shown and described.
